FIG. 1.

FIG. 2.

FIG. 3.

INVENTOR:
Frank H. Adler
BY his ATTORNEY:
A. M. Carlsen

UNITED STATES PATENT OFFICE.

FRANK H. ADLER, OF MINNEAPOLIS, MINNESOTA.

WINDSHIELD-CLEANING COMPOSITION.

1,378,931.

Specification of Letters Patent. Patented May 24, 1921.

Application filed June 17, 1919. Serial No. 304,935.

To all whom it may concern:

Be it known that I, FRANK H. ADLER, a citizen of the United States, residing at Minneapolis, in the county of Hennepin and 5 State of Minnesota, have invented a new and useful Windshield-Cleaning Composition, of which the following is a specification.

My invention relates to means for cleaning moisture and dust away from the wind shields of automobiles and other glass; and 10 the object is to provide a handy and efficient device for said purpose.

In the accompanying drawing Figure 1 is 15 a top or back view of the device with a hand in dotted outline shown as holding the device during its operation. Fig. 2 is an edge view of the device with a small portion broken away so as to expose the inner structure. Fig. 3 is a cross section of the handle 20 on the line 3—3 in Fig. 2.

Referring to the drawing by reference numerals, the device is mainly a wiping pad or cushion, the form and materials of which 25 are essential to the make-up of the invention. The handle 4 and the back 5 are made of oil cloth or other water-proof material so as not to get softened by water. To insure this the handle when made of oil cloth is made of a 30 strip of oil cloth turned with the oiled side outward and folded along the middle as at 6 in Fig. 3, and also folded at 7 and its edges 8 brought back into the fold 6, and the handle stitched or sewed as at 9. Said handle 35 is then sewed at 11 to the back piece 5, and the latter is sewed at 12 with its edges to the edges of a bulging chamois skin 13. The latter is pierced with very small perforations 14.

40 Within the bulge 13 is placed a sack, 15, which is made of cheese-cloth or similar material and is filled with a water absorbing material 16.

Said absorbent material is in the form of a powder and is composed of the following 45 ingredients in about the following proportions—viz., one pound machine oil, two pounds turpentine, sixteen pounds granulated tobacco, sixteen pounds bran and one-hundred-forty-four pounds of wood ashes. 50 The ingredients should be well mixed and put into the cheese cloth bag and the latter placed into the chamois skin bag before it is completely sewed to the back 5.

In the operation or use of the device when 55 a wind shield or other window or glass has its transparency more or less obstructed by moisture, the operator inserts some of his fingers in the handle 4 and rubs the glass with the pad 13, with the result that the 60 moisture is absorbed by the absorbent material and the chamois skin fully cleans the glass. If there be much moisture, or if the glass is covered with dry dust or mud so 65 that it must be washed by water and other means before this device can be applied, and the pad should thus be subjected to an extra large amount of moisture, it can be easily dried again by exposing it to either heat or 70 draft, as the perforations admit of evaporation of such moisture as the absorbent material can not absorb with the desired haste.

What I claim is:

A mixture for the purposes set forth, said mixture being in the form of a powder and 75 composed of the following ingredients in about the following proportions: one pound machine oil, two pounds turpentine, sixteen pounds tobacco, sixteen pounds bran and one hundred and forty-four pounds of wood 80 ashes.

In testimony whereof I affix my signature.

FRANK H. ADLER.
